UNITED STATES PATENT OFFICE.

GEORGE E. PATTON, OF MONMOUTH, ILLINOIS.

DESIGN FOR A POTTERY JAR.

No. 39,206.

Specification for Design.

Patented March 17, 1908.

Application filed December 2, 1907. Serial No. 404,978. Term of patent 14 years.

To all whom it may concern:

Be it known that I, GEORGE E. PATTON, a citizen of the United States, residing at Monmouth, in the county of Warren and State of Illinois, have invented a new, original, and ornamental Design for Pottery Jars, of which the following is a specification, reference being had to the accompanying drawing, which is hereunto annexed, and is a part thereof.

The figure is a side elevation of a pottery jar showing my new design.

I claim:

The ornamental design for a pottery jar as shown.

GEORGE E. PATTON.
